UNITED STATES PATENT OFFICE.

STANISLAS BEAUREGARD, OF ST. HENRY, CANADA, ASSIGNOR TO JOSEPH ADAM, OF MONTREAL, CANADA.

NAIL-MAKING MACHINE.

SPECIFICATION forming part of Letters Patent No. 772,916, dated October 25, 1904.

Application filed May 18, 1903. Serial No. 157,569. (No model.)

To all whom it may concern:

Be it known that I, STANISLAS BEAUREGARD, a subject of the King of Great Britain, residing at St. Henry, county of Hochelaga, Province of Quebec, Canada, have invented certain new and useful Improvements in Nail-Making Machines; and I do hereby declare that the following is a full, clear, and exact description of the invention, such as will enable others skilled in the art to which it appertains to make and use the same.

My invention relates to nail-making machines, and especially to that class which make what is known as "wire" nails.

15 The object of the invention is to produce a machine for the purpose mentioned which is very simple in construction and which embodies an improved arrangement and mode of operation of the dies which form the nails.

20 It should be stated that the machine belongs to that class which form the nails in a continuous strip or wire as it passes through the machine.

The invention consists in the construction 25 and combination of parts to be more fully described hereinafter, and definitely set forth in the claims.

In the drawings, which fully illustrate my 30 invention, Figure 1 is a longitudinal vertical section of the machine. Fig. 2 is a transverse vertical section taken substantially on the line 2 2 of Fig. 1. Fig. 3 is a side elevation of a portion of the mechanism, this view being upon a reduced scale and taken looking 35 in the same direction as Fig. 1. Fig. 4 is a view taken at the dies, certain of the parts being shown in elevation and others in vertical section, as will appear. This view is upon an enlarged scale. Fig. 5 is an elevation of 40 certain of the dies upon an enlarged scale. It represents substantially a portion of the dies as shown in Fig. 2.

Throughout the drawings and specification the same numerals of reference denote like 45 parts.

Referring more particularly to the parts, 1. represents the base of the machine, from which rise the oppositely-disposed standards 2, which standards support a substantially 50 horizontally rectangular plate 3, beneath

which there are disposed a pair of alining bearings 4, as shown, and these bearings support the main shaft 5 in the manner indicated, the same being provided at its outer extremity with a fly-wheel 6, adjacent to which are the 55 tight and loose pulleys 7 and 8, as shown, which pulleys afford means for driving the shaft 5, as will be readily understood.

Upon the upper side of the aforesaid plate 3 there is mounted a block 9, attached to the same by suitable bolts 10. This block has a substantially vertical face 11, which is preferably square in form, as shown in Fig. 2. In this face 11 there is provided a transversely-disposed guide-slot 12, preferably of dovetail 65 form, as shown. The upper edge 13 of this slot passes continuously from edge to edge of the face 11, as shown; but the lower edge 14 is interrupted at one side by an abutment 15 in the manner shown most clearly in Fig. 2. 70 Upon this vertical face 11, across the said guide-recess 12, there is provided a vertical plate 16, which is attached by means of suitable screws 17, as shown, and in the recess or guide 12 behind this plate there is placed an anvil-die 75 18, which consists substantially of a block of general rectangular form, but which has a beveled edge received by the lower edge 14 of the guide 12. It should be understood that this anvil-die is normally maintained in a fixed 80 position by means of the screws or bolts 19 and 20, which are mounted, respectively, in the abutment 15 and the plate 16, as shown. The extremity of the bolt 19 abuts the outer face of the anvil-die 18, and the extremity of the screw 20 is received in the longitudinally-disposed slot 21, which is formed in the lateral face of the anvil-die 18, as shown. Opposite to the said anvil-die 18 there is mounted a clamping-die 22, which is adapted to slide in 85 the said guide 12, being provided with beveled edges 23 for this purpose, as will be readily understood. The inner extremity of this die 22 is cut away at its upper edge, as indicated at 24, so as to form a substantially horizontal face 25, which is in substantial alinement with the upper face 26 of the aforesaid anvil-die 18. As illustrated most clearly in Fig. 5, the adjacent upper edges of these dies 18 and 22 are formed, respectively, with con- 90

cave recesses 27 and 28, and these recesses, it should be understood, are adapted to coöperate to hold or clamp between them a wire 29, which is adapted to be passed between the 5 dies. In order to allow the wire 29 to pass in the manner suggested, the said block 9 is provided with a guide-opening 30, which is provided with a sleeve 31, through which the wire passes, as indicated in Fig. 1. The manner of controlling the feeding movement of 10 this wire will be described more fully herein-after.

Upon the upper face 26 of the anvil-die 18 there is mounted a pointing-die 32, which has 15 a beveled upper edge 33, coöoperating with the edge 13 of the guide 12, and it should be understood that this die 32 is adapted to slide longitudinally in the guide 12. Without going into the details of the operation at this 20 point it may be stated that when the wire 29 is clamped, in the manner already suggested, between the dies 18 and 22 the die 32 is advanced in such a manner as to shear or cut off a portion of the wire in such a manner as to 25 form a point for the nail. For this reason the lower edge 34 of the die 32 is tapered, as shown most clearly in Fig. 4.

For the purpose of actuating the die 22 the aforesaid shaft 5 is provided with a cam 35, 30 which cam actuates the bell-crank lever 36 through the medium of the frictional roller 37, the said bell-crank lever being mounted upon a suitable bracket 38, which bracket is attached to the under side of the plate 3 35 aforesaid by means of suitable bolts 39. To the upper extremity of the vertical arm 40 of the bell-crank lever 36 there is pivotally attached a knuckle 41, which knuckle lies adjacent to the bracket 42, which bracket is pivotally carried at 42° upon the outer extremity 40 of the die 22, as shown. In the knuckle 41 and the bracket 42 there is mounted an adjusting-bolt 43, having oppositely-disposed extensions 44, which are oppositely threaded, 45 as will be readily understood, so that the rotation of the bolt will bring together or separate the knuckle and the die. The lower arm 45 of the aforesaid bell-crank lever 36 carries an adjustable stop-bolt 46, the upper extremity 47 of which abuts against the lower side of the aforesaid plate 3 in order to limit the movement of the bell-crank lever in one direction, as will be readily understood, and a spring 48 is provided which constrains the 50 said bell-crank lever in a way to maintain the said extremity 47 against the said plate 3, in this manner normally maintaining the roller 37 against the face of the cam 35 in the manner shown. It should be understood that this 55 bolt 46 passes through the opening 48a in the arm 45 and is adjustable longitudinally therein by reason of nuts 49. In order to actuate the die 32, an arrangement very similar to that described for actuating the die 22 60 is adopted. To this end a cam 50 is pro-

vided, which is carried by the aforesaid shaft 5 and the lateral face of which is provided with a cam-groove 51, in which groove runs a friction-roller 52, the same being mounted upon the extremity of the lower arm 53 of a 70 bell-crank lever 54, which bell-crank lever is substantially similar to the aforesaid bell-crank lever 36. The arrangement for attaching the upper extremity of the bell-crank lever 54 to the die 32 is similar to the arrangement for attaching the bell-crank lever 36 to the die 22. This connection comprises a knuckle 55 and a bracket 56, which are pivoted, respectively, to the lever and the die, as shown, there being mounted between them 80 an adjusting-bolt 57, comprising oppositely-disposed extensions 58a, which are oppositely threaded, as will be readily understood. The bell-crank lever 54 is mounted upon a bracket 58, carried by the under side of the plate 3, 85 which bracket is substantially similar to the bracket 38 aforesaid.

The dies which form the heads of the nails or which coöperate to form the heads of the nails will now be described, together with the 90 mechanism for actuating them.

Upon the face 11 aforesaid there are provided a pair of oppositely-disposed bosses 59, which are preferably of crowned or convex form, as shown in Fig. 1. In these bosses 95 are mounted, respectively, the studs 60, and upon these studs there are loosely mounted the oppositely-disposed levers 61, which are arranged substantially vertically, as shown most clearly in Figs. 1 and 3. At their upper extremities the faces 62 of these levers which are adjacent to the face 11 aforesaid are provided with undercut recesses 63, which are adapted to receive the dies 64, which dies have beveled lower edges 65 to correspond 100 with the undercut notches 63 and are retained in place by means of clamps 66, as shown. Near their rear faces these dies have recesses 64a for a purpose which will appear herein-after. It should be understood that these 105 two dies 64 are placed opposite to each other in such a manner that their adjacent vertical faces 67 may coöperate to clamp between them the wire 29. The mechanism for actuating these levers 61 will now be described. 110 It consists simply of a cam 68, which is rigidly carried by the aforesaid shaft 5 and upon the face of which run the friction-rollers 69, carried by the lower extremities of the levers 61, as shown. It should be understood that 115 in the operation of the machine the dies 64 clamp the wire between their faces 67, and after the wire has been securely clamped in this manner they are moved toward the dies 18 and 32 in such a manner as to form a head 120 between the faces of the dies, the operation in this respect being substantially the same as that found in other machines. In order to enable the levers 61 to rock upon the pivot-studs 60, the openings 70 through the levers 125 130

to receive the said studs are of increased diameter near the faces of the levers, as indicated. As indicated most clearly in Figs. 1 and 2, the said table 3 is provided with a large opening 5 71, through which the aforesaid levers 61 pass, and in this same opening there is mounted a substantially vertical rocking lever 72, the same being pivoted at 73 upon a bracket 74, which bracket is mounted upon the upper 10 face of the aforesaid plate 3 and adjustable longitudinally with respect to the wire 29 by reason of an elongated slot 75, through which slot a bolt 76 passes, the said bolt being mounted in the plate 3, as indicated. Near its upper 15 extremity this rocking lever is provided with an opening 77; through which the wire 29 passes freely, and at the sides the rocking lever 72 has attached thereto links 78, which connect the same with the aforesaid levers 61, 20 respectively. The lower extremity of the lever 72 carries a friction-roller 79, which runs upon the face 80 of a cam 81, which cam is mounted upon the aforesaid main shaft 5. A spring 82, which is received by a hook 83, affords means for constraining the lever 72 into 25 such a position as will retain the roller 79 in contact with the cam 81. It should be understood that as the shaft 5 rotates the cam 81 operates to rotate the rocking lever 72 upon 30 its pivot 73 in such a manner as to rock the levers 61 forwardly through the medium of the links 78. This forward movement, however, of the levers 61 and the dies 64 takes place when the wire has been clamped between the dies 64, and the forward movement 35 of the dies forms the heads of the nails, as already stated.

Arrangement is made for advancing or feeding the wire 29 through the machine, it being advanced periodically an amount substantially equal to the length of one nail. To this end the aforesaid block 9 and the plate 3 are provided with an opening 84, which passes through the same, and in this opening there 40 is mounted a feed-lever 85, which is pivotally mounted upon a pin 86, carried by the aforesaid block. Near the upper extremity of this lever there is provided a rest 87, across which the wire 29 passes, and above this rest 45 there is arranged a feed-dog 88, which is pivoted at 89 and provided with a sharp edge 90, which is disposed in the direction in which the wire is to be advanced and which lies adjacent to the upper face of the aforesaid rest 50 in such a manner that the wire may be clamped thereupon, so as to advance the same, as will be readily understood. This lever is actuated from time to time by means of the rear face 91 of the aforesaid cam 50, which 55 face cooperates with a friction-roller 92, which is carried by the lower extremity of the feed-lever 85, as shown in Fig. 1, the said roller being constrained against the cam by means of the aforesaid spring 82, which 60 spring was described in connection with the

rocking lever 72. It will be observed that the extremity of this spring opposite to the hook 83 is attached in an opening 93, provided in the feeding-lever 85, as shown. It should be understood that as the nails are 65 formed in the wire the continuity of the wire is not broken and the operation of forming the nails consists virtually in changing the form of the wire, so that it constitutes a succession of nails, the points of the nails being formed just 70 behind the heads 96 of the nails next in advance, as indicated in Fig. 1. Arrangement is made for preventing a retrogressive movement of the wire. To this end a block 97 is mounted near that part of the machine where 75 the wire leaves the same, and upon this block is supported a rest 98, over which the wire passes and above which there is located a detent finger or pawl 99, having a sharpened point, as shown, and constrained by means of 80 a spring 100 against the rest, as shown. As indicated, the wire 29 passes between the detent-finger 99 and the rest 98 in such a manner that the point of the finger 99 may engage behind the heads 96 of the nails in order 85 to prevent any possible retrogressive movement of the wire, as will be readily understood. In the lower portion of the block 97 there is mounted a set-screw 101, the extremity of which abuts against the outer face of 90 the aforesaid member 74, in this manner facilitating the longitudinal adjustment of the member 74, which adjustment is made possible by the presence of the elongated slot 75 and made necessary in order to bring the co-operating dies into proper relation with each other in forming the heads of the nails. Before the wire passes into the machine it passes through a guide or eye 102, which is carried above a suitable post 103, and behind this 105 guide there is arranged certain straightening-rollers 104, which co-operate to straighten the wire in the usual manner. After passing from the machine the wire 29 is wrapped upon a reel 105, which reel is constrained to rotate 110 in the proper direction by a comparatively loose cross-belt 106, which belt may be driven by the continuously-moving belt-pulley 107, the said belt-pulley receiving its motion through the medium of a worm-wheel 108 115 coaxial therewith, which engages a worm or screw 109, formed upon one extremity of the aforesaid shaft 5. A bracket 110, arranged at this point, constitutes a bearing or support for the aforesaid worm-wheel and pulley. The 120 aforesaid crossed belt 106 passes about the pulley 111, which is rigid with the aforesaid reel 105, and the pulley and reel are both supported upon a suitable bracket 112 in any suitable manner.

In operation it should be understood that the shaft 5 is continuously driven, and this shaft, by means of the cam 91, affords means for advancing the wire 29 periodically by reason of the feed-lever 85. Beyond the feed- 125

lever the wire passes between the fixed or anvil die 18 and the movable clamping-die 22, which dies together constitute gripping or clamping dies, which periodically operate to 5 clamp the wire therebetween. The die 18 is substantially fixed, arrangements being made, however, for adjusting the same; but the die 22 is movable and is from time to time advanced or withdrawn by means of a bell-crank 10 lever 36, which is actuated by a cam 35 on the main shaft 5. It should be understood that when the wire 29 is being advanced by the feed-lever the dies 18 and 22 are maintained apart, so as to permit such an advance, 15 and after the advance is completed these dies then coöperate to clamp the wire between them. They clamp the wire at their upper edges by means of the concave recesses 27 and 28 aforesaid, which recesses are, by the way, 20 of little depth, so that the upper portion of the work or wire when clamped protrudes laterally above the dies and above their upper faces. When clamped in this manner, the pointing-die 32 is advanced, sliding upon the 25 upper faces of the dies 18 and 22 in such a manner as to shear off a portion of that part of the wire which protrudes above the recesses 27 and 28, in this way forming the point of the nail. This die 32 is actuated by 30 means of the bell-crank lever 64, which receives its motion from the cam-groove 51, formed in the cam 50. While the wire 29 is clamped between the dies 18 and 22 and preferably while the point is being formed the 35 dies 64 are advanced in such manner as to clamp the wire between them. These dies are advanced by reason of the cam 68, which operates through the rollers 69 to throw apart the lower extremities of the levers 61, which 40 carry the said dies 64. After the dies 64 have clamped the wire in the manner described the levers 61 are then rocked in such a way as to move the dies 64 toward the outer faces of the dies 18, 22, and 32. In this way 45 the head of the nail is formed. Upon being released by the dies the wire is again advanced by the feed-lever 85, and the operation just described is repeated. In Fig. 5 the dotted lines indicate how the clamping-dies 50 operate to hold the wire while the point is being formed. It should be understood that the rocking movement of the lever 61, which movement forms the head, is possible on account of the form of the opening 70, the said 55 opening being of enlarged diameter at the faces of the levers, as described. As the wire 29 is advanced the head of the nail which had just been formed is received in the aforesaid recesses 64^a, which recesses are formed 60 for that purpose.

While I have shown in the accompanying drawings the preferred form of my invention, it will be understood that I do not limit myself to the precise form shown, for many 65 of the details may be changed in form or po-

sition without affecting the operativeness or utility of my invention, and I therefore reserve the right to make all such modifications as are included within the scope of the following claims or of mechanical equivalents to 70 the structures set forth.

Having described my invention, what I claim, and desire to secure by Letters Patent, is—

1. In a nail-machine, in combination, a pair 75 of oppositely-disposed dies having substantially alining faces, a third die adapted to slide upon said alining faces, said first dies having oppositely-disposed recesses adapted to clamp the work at said alining faces, said third die 80 being adapted to shear a portion of the work to form a point.

2. In a nail-machine, in combination, a pair 85 of oppositely-disposed dies having substantially alining faces, a third die slidably mounted upon said faces, said pair of dies having oppositely-disposed recesses formed in said alining faces, and means for actuating said dies, said third die being adapted to shear a portion 90 of the work clamped between said pair of dies.

3. In a nail-machine, in combination, a movable die, a block having a guide therefor, means for passing the work transversely with respect to said guide, a substantially fixed 95 die, said dies having substantially alining faces, and being provided with means for clamping the work adjacent to said alining faces, so constructed that a part of said work protrudes above said faces, and a third die 100 movably mounted in said guide, and slidable upon said faces, said third die being adapted to shear a portion of said work.

4. In a nail-machine, in combination, a die 105 having an upper face and a second face substantially at right angles thereto, with a recess formed at the meeting edge of said faces, a second die having an upper face and a second face disposed transversely thereto, said second die having a recess at the edge formed by the meeting faces thereof, said recesses being adapted to clamp a body protruding beyond said upper faces, and a shearing-die 110 slidably mounted upon said upper faces.

5. In a nail-machine, in combination, a pair 115 of dies having flush faces and coöperating recesses at the adjacent edges of said flush faces, said coöperating recesses constituting together an incomplete cross-section of a cylindrical body, means for actuating said dies 120 to clamp a body in said recesses, and a shearing-die slidably mounted upon said flush faces and adapted to shear the portion of said body protruding above said flush faces.

In witness whereof I have hereunto set my 125 name in the presence of two witnesses.

STANISLAS BEAUREGARD.
